[57] CLAIM

The ornamental design for a audio interface module for use with a data processing system, as shown and described.

DESCRIPTION

FIG. 1 is a front perspective view of an audio interface module for use with a data processing system showing our new design;

FIG. 2 is a side elevational view thereof;

FIG. 3 is a top plan view thereof;

FIG. 4 is a side elevational view thereof; taken from the opposite side illustrated in FIG. 2;

FIG. 5 is a front elevational view thereof; and,

FIG. 6 is a rear elevational view thereof.
